UNITED STATES PATENT OFFICE.

HENRY W. LAUN, OF CHICAGO, ILLINOIS.

ACETYLENE-GAS GENERATOR.

1,244,618.

Specification of Letters Patent. Patented Oct. 30, 1917.

Application filed July 6, 1915. Serial No. 38,051.

To all whom it may concern:

Be it known that I, HENRY W. LAUN, a citizen of the United States, residing at Chicago, in the county of Cook and State 5 of Illinois, have invented new and useful Improvements in Acetylene-Gas Generators, of which the following is a specification.

This invention relates generally to improvements in acetylene gas generators of 10 the bell type in which water is fed into a carbid receptacle, but relates more specifically to improvements upon my Patent No. 1,052,070, dated February 4th, 1913.

In the construction embodied in this patent, the valves in the water inlet and gas outlet pipes extending from the respective carbid containers are each provided with a manually operable lever for controlling the position of said valves. These levers are 20 arranged to swing outwardly in opposite directions toward the sides of the generator. As a result, the gas generator could not be placed in the corner of a room, nor with one side thereof in close proximity to the 25 side of the room, as the inner valve controlling lever would necessarily strike the wall and prevent the proper manipulation thereof. Furthermore, in this construction, means were not provided to insure either or both 30 closures of said carbid containers being closed and locked, previous to the opening of the valves controlling the water inlet and gas outlet pipes associated with each container. As a result, it often happened that 35 when one of said containers was being recharged with carbid, water was permitted to mix with the carbid and thereby generate gas before the closure of said container was closed and locked in said closed position.

40 One of the objects of my invention is, therefore, to provide a gas generator of the type above noted, in which the manually operable levers are arranged to swing outwardly in the same general direction toward 45 one side of the gas generator and thereby permit said generator to be positioned closely in a corner or against the side of a room.

Another object of the invention is to provide a swinging closure for each carbid con-

tainer, which, when opened, will be so positioned relative to the manually operable valve controlling lever that said lever will, during its movement to open said valve, engage and move said closure to its closed or 55 operative position previous to said valve being opened.

Another important object of the invention is to provide a locking mechanism for the closure which is shiftable into and out 60 of locking position and which will be automatically moved to its locking position by a further movement of the manually operable lever to a direction to open the valves after the closure has been moved by said 65 lever to its closed position.

These and other objects of my invention will be hereinafter more fully disclosed.

In the drawings which show by way of illustration, one embodiment of my invention,

Figure 1 is a side elevation of a gas generator constructed in accordance with my invention;

Fig. 2 is a partial rear elevation thereof;

Fig. 3 is a horizontal sectional view taken on the line 3—3 of Fig. 1;

Fig. 4 is a vertical sectional view taken on the line 4—4 of Fig. 3;

Fig. 5 is a detail view showing the automatic means for controlling the flow of water to the carbid container;

Fig. 6 is a detail perspective view of the rear end of one of the carbid receptacles;

Fig. 7 is a perspective view of the outer 85 end of one of said carbid containers, showing the valve in its closed position, the closure for the opening of said container in its open position, and the locking mechanism for said closure in its open position;

Fig. 8 is a detail top plan view of the latch shown in Fig. 7;

Fig. 9 is a detail side elevation thereof;

Fig. 10 is a detail plan view showing a modified form of latch;

Fig. 11 is a detail front elevation of one of said carbid containers, and

Fig. 12 is a fragmental view of a portion of the locking hasp and a part of one of the arms of one of the containers showing means 100

for holding the hasp in its inoperative position as well as for automatically assisting in causing it to assume its operative position.

[5] In the drawings, the gas generator is shown as comprising a tank 5 which is divided into upper and lower compartments 6 and 7 respectively. The upper compartment is substantially filled with water and [10] this water forms a seal for the bell or gasometer 8, the water being delivered to the compartment from the inlet spout 9.

The lower compartment 7 is also filled with water and this water is supplied from [15] a vessel 10 through suitable piping, said vessel 10 being preferably arranged in one side of the exterior of the tank 5, from which it is supported.

Disposed within the lower compartment [20] are two carbid containers 11 and 12 respectively. These containers project outwardly from the compartment through suitable openings in the wall of the tank, and the outer end of each container is provided with [25] an opening 13 for the insertion or removal of a carbid receptacle 14, which is normally disposed within the container. The projecting portion of each container is surrounded, except at its opening 13, with a [30] water jacket 15.

Each carbid receptacle 14 is provided with a plurality of compartments 16, which are partially filled with carbid. At the rear end, the receptacle is provided with a compartment [35] 17 having a raised bottom 18, for receiving the water from the vessel 10. The construction of these receptacles, and the action between the water and carbid are substantially identical as shown and described [40] in my previously mentioned patent and further description is deemed unnecessary.

The water vessel 10 is equally divided into two compartments 10^a and 10^b, and extending from the compartment 10^a is a pipe 20, [45] which communicates with the rear end of the carbid container 11, a trap 21 being formed by said pipe in advance of its connection with said container. A pipe 22 connects the compartment 10^b with the pipe [50] 20 and at the juncture there is provided a three way valve 23. Between the trap 21 and the valve 23, the pipe 20 is provided with a three way valve 24, and extending from this valve is a pipe 25 having a trap [55] 26 formed thereby and communicating with the rear end of the carbid container 12 above the compartment 7 thereof. These valves 23 and 24 are simultaneously actuated by a connection 27 to permit water from the compartment 10^a entering the carbid container 11, or said valves are reversed to permit water from the compartment 10^b entering the carbid container 12. The water from both compartments 10^a and 10^b, however,

never enters both carbid containers 11 and 12 at the same time. As a result, gas can be continuously generated by either one of said carbid containers while the other is idle or being replenished.

The gas generated in the carbid compartment 11 passes outwardly through pipe 28 which is connected to the projecting portion of said container adjacent the opening 13 thereof, and thence through pipe 29 to the dome of the bell or gasometer 8 above the [75] water line.

The gas generated in the carbid compartment 12 passes outwardly through pipe 30 and thence through pipe 29 to the dome of said gasometer. Inasmuch as gas is never [80] generated in both carbid containers at the same time, valves 31 and 32 are respectively arranged in the pipes 28 and 30 at points above the projecting portions of the carbid containers. In order to control the passage [85] of water in the pipes 20 and 25 below the valve 24, whereby either or both supplies of water may be interrupted, valves 33 and 34 are respectively arranged in said pipes 20 and 25.

The valve stem of the valve 31 of the gas outlet pipe 28 is provided with a manually operable actuating means consisting of an arm or lever 35. This lever is connected by a link 36 to an arm 37 fixed to the valve stem of the valve 33. As a result, when the lever 35 is in the position shown in Fig. 3, both valves 31 and 33 are open to permit the ingress of water and egress of gas from the carbid container 11. When it is desired to relieve the carbid container 11 from further action, or for replenishing the same, the lever 35 is swung toward the tank 5 to the position shown in dotted lines in Fig. 3. This movement of the lever, through the link 36 and arm 37, moves both valves 31 and 33 to closed positions.

A similar lever 38 is connected to the valve stem of the valve 32 in the gas outlet pipe 30, and this lever is connected by a link 39 with an arm 40 fixed to the valve stem of the valve 34. The link 39 extends under the link 36, and these links are supported on the tank 5, for slideable movements, in bearings 41 and 42 respectively. As a result, when it is desired to relieve the carbid container 12 from further action, or for replenishing the same, the lever 38 is swung in the same general direction as noted in connection with lever 35. This movement of lever 38 closes the valves 32 and 34 in the gas outlet and water inlet pipes respectively.

It will thus be observed that the levers 35 and 38 are arranged to be moved in the same general direction, and that the connecting links are disposed on one side of the tank 5. This construction permits the generator to be placed in close proximity to the corner of

a room, or arranged to have the side thereof opposite the links directly against a side of the room.

Each carbide container is provided with a closure and a locking mechanism therefor, and inasmuch as the construction and operation of each closure and locking mechanism is identical, a description of one will suffice.

A closure 43 for the opening 13 of each 10 water jacket 15 is mounted upon horizontal pivots 44-44, supported at the top of said water jacket. As a result, the closure 43 can be swung upwardly and thence backwardly to an inclined position in rear of a vertical 15 plane passing through said pivots. The lever 35 extends outwardly and thence downwardly, as at 45, and this downwardly extending portion is then bent forwardly to form a hand piece 46. The laterally extending portion of this lever is of a length 20 sufficient to engage the closure 43 when the latter is in its closed position, as shown in Fig. 7, and swing said closure about its pivots until said closure is moved forwardly to a 25 point in advance of the vertical plane extending through the pivots 44. The closure 43 will then gravitate to its closed position.

The locking mechanism for the closure comprises spaced arms 47 and 48 which 30 respectively extend forwardly from the water jacket 15 on opposite sides of the opening 13. The arm 47, which is adjacent the lever 35, supports at its outer end, a laterally swinging hasp 49. When the hasp is swung across the closure 43 to its locking position, the free 35 end thereof enters the mouth 50 at the outer end of the arm 48. The upper jaw 51 of said mouth is provided with a vertical opening 52 and a latch 53 is disposed in said opening 40 and is fulcrumed on a horizontal pivot pin 54, as clearly shown in Figs. 8 and 9. This pin is located at the rear end of said jaw, and the latch is provided at its pivotal point with a trip arm 55 which, when the latch is 45 swung upwardly, is in position to be engaged by the free end of said hasp and thereby caused to be automatically moved to its position to lock said hasp against movement. Carried by the hasp is a clamping screw 56 50 which is manually operable to seal the closure against its seat.

Each of the levers 35 and 38 is secured to one of the clamping screws 56 by a lock block, 45^a, which is loosely mounted at one of its 55 ends on the lever, said end being bent around the lever as particularly shown in Fig. 7, and has its opposite end formed with a hook which is adapted to be fitted over the projecting portion of the screw 56, as illustrated 60 in Figs. 1, 3 and 4.

The pendent loosely swinging position of the block 45^a, when disconnected or unhooked from the clamping screw is indicated in Fig. 7.

From the foregoing it will be readily understood that when it is desired to replenish one of the carbide containers, the controlling lever 35 is swung outwardly to the position shown by dotted lines in Fig. 3. This movement closes the gas outlet valve 31 and the water inlet valve 33 associated with the carbide container 11. The latch 53 is then released, the hasp 49 swung to the position shown in dotted lines in Fig. 3, and the closure 43 is swung upwardly and rearwardly as previously described. The closure and the locking mechanism therefor are now disposed in their open positions. After the container has been replenished, the lever 35 is returned to its initial position, and before the valve 31 is opened by said lever, said lever will engage the closure 43 and cause the same to be moved to its closed position. Immediately following the movement of said closure 43 to its closed position, 85 and before the valve 31 is opened, the downwardly extending portion 45 of said lever 35 will engage the hasp 49 and swing the same to its locking position, the free end of said hasp engaging the trip arm 55 of 90 said latch and causing the latter to become automatically locked. The clamping screw 56 can then be adjusted to securely seal the closure 43 against its seat.

In order to maintain the latch 53 in its receiving position, I have provided one or more spring washers 57 on the pivot pin 54 between said latch and the wall of the opening.

In the modified form of latch, as shown 100 in Fig. 10, the arm 48 is provided on one side with a spring latch 53^a, and a locking pin 53^b is removably mounted in suitable 105 openings formed in the arm 48 in advance of the hasp 49.

The gas in the bell or gasometer 8 passes outwardly through the pipe 58, and located in this outlet or service pipe is a controlling valve 59.

In order to automatically maintain a certain amount of gas within the gasometer, I provide a valve 60 in the water pipe 20, and fixed to the valve stem of said valve 60 is a forked arm 61, which is adapted to be engaged by a trip arm 62 carried by the gasometer 8. In operation, as the supply of gas in the gasometer diminishes, said gasometer will, of course, descend and carry with it the trip arm 62, which will engage the forked arm 61 and open the valve 60, thereby allowing water to enter the predetermined carbide container. After a predetermined amount of gas has been generated, the upward movement of the gasometer, due to the additional supply of gas, will carry 120 upwardly with it the trip arm 62, which will again engage the forked arm 61 and close the valve 60.

In Fig. 12, I have shown a modified construction of the hasp 49, which consists in securing a spring 49^a at one of its ends to the hasp, at a suitable distance from its pivot point, and at its other end to the arm 47.

This spring will act to hold the hasp in its open position until it is struck by the free portion of the lever 35 or 38 when the same is moved to open its valve, when it is obvious, the hasp will be swung on its pivot toward its locking position, in which operation the spring will exert itself to automatically force the hasp against the closure and thus seal the same in the opening before any gas can escape from the container.

The pipe-sections 28^a and 30^a are coupled to the pipes 28 and 30 respectively and communicate with the compartment 7 and are employed to vent their respective containers.

Having thus described my invention, what I claim is:

1. In a gas generator, the combination of a tank, a carbid container fixed in said tank and having an opening through which a carbid receptacle can be inserted or removed from the container, a water supply pipe leading to said container, a gas conducting pipe leading from the container, valves in said pipes, a closure for the opening in the container hinged to the top edge thereof, locking means for said closure hinged to the container at one side of the opening therein, said locking means being shiftable into and out of locking position at an angle to the opening and closing movement of the closure and a manually operable lever controlling the valves and constructed and arranged to automatically shut the closure and shift the locking means into locking position as the valves are opened.

2. In a gas generator, the combination of a tank, a carbid container fixed in said tank and having an opening through which a carbid receptacle can be inserted or removed from the container, a water supply pipe leading to said container, a gas conducting pipe leading from the container, valves in said pipes, a closure for the opening in the container, locking means for said closure, said locking means being shiftable into and out of locking position, one of the valves being on the opposite side of the tank from the container, a manually operable lever mounted on the same side of the tank as the container, a curved link extending from the lever around the tank and operatively connecting to the oppositely located valve and mechanism extending from the lever to the closure and locking mechanism and constructed and arranged to automatically shut the closure and shift the locking means into locking position as the valves are opened.

3. In a gas generator, the combination of

a tank, a carbid container fixed in said tank and having an opening through which a carbid receptacle can be inserted or removed from the container, a water supply pipe leading to said container, a gas conducting pipe leading from the container, valves in said pipes, a closure for the opening in the container hinged to the top edge of the opening, locking means for said closure hinged to one side of said opening, a manually operable lever controlling the valves, means connected to said lever adapted to close the closure as the lever is moved to open the valves, and means operable by a further movement of the lever after the closure is shut to shift the hinged locking means to its locking position.

4. In a gas generator, the combination of a tank, a carbid container in said tank having an opening, gas and water valves for said container, a closure for the opening in the container hinged to the top edge of the opening and adapted to swing in a vertical arc in opening or closing, locking means for said closure hinged to a side edge of the opening and adapted to swing into and out of locking position in a horizontal arc and a lever controlling the valves, the closing of the closure and the swinging of the locking means to a locking position.

5. In a gas generator, the combination of a tank, a carbid container in said tank having an opening, gas and water valves for said container, a closure for the opening in the container hinged to one edge of the opening, locking means for said closure hinged to another edge of the opening, one of said valves being located in front and in proximity to the opening in the container and another being located in the rear of the container on the opposite side of the tank, a controlling lever connected to the valve in front and a link connected to said lever and curved around the side of the tank with its rear terminal connected to the rear valve, an angular extension of the lever being arranged to close the locking means, and said lever being adapted to contact with and shut the closure before the locking means is moved as said lever is moved to open the valves.

6. In a gas generator, the combination of a tank, a plurality of separate carbid containers fixed in said tank, each having an opening through which a carbid receptacle can be inserted or removed from the container, a water supply pipe leading to each container, a gas conducting pipe leading from each container, valves in said pipes, an independent closure for the opening in each container, locking means for each of said closures, each of said locking means being shiftable into and out of locking position, one of the valves of each container being

on the opposite side of the tank from the container, a manually operable controlling lever for each closure, a curved link extending from each of said levers around the side 5 of the tank and operatively connecting to one of the oppositely located valves, and shifting mechanism extending from each of

the levers to the closure it controls and the locking mechanism therefor.

HENRY W. LAUN.
